(57) **CLAIM**

The ornamental design for a power controller housing, as shown and described.

DESCRIPTION

FIG. 1 is a perspective view of a power controller housing showing our new design;

FIG. 2 is a back elevation view thereof;

FIG. 3 is a front elevation view thereof;

FIG. 4 is a bottom plan view thereof;

FIG. 5 is a top plan view thereof;

FIG. 6 is a left side view thereof; and,

FIG. 7 is a right side view thereof.

The broken lines are included for the purpose of illustrating environmental structure and form no part of the claimed design.
